UNITED STATES PATENT OFFICE.

HENRY NELSON SCHOFIELD, OF FREDERICK, MARYLAND.

COOLER ATTACHMENT FOR ENGINES.

Application filed September 8, 1921. Serial No. 499,299.

To all whom it may concern:

Be it known that I, HENRY N. SCHOFIELD, a citizen of the United States, residing at Frederick, in the county of Frederick and State of Maryland, have invented certain new and useful Improvements in Cooler Attachments for Engines, of which the following is a specification.

The invention relates to pump attachments, for automobile engines and the like, in the nature of an engine cooler, for promoting a relatively rapid circulation of the cooling fluid, ordinarily water, from the bottom of the radiator and thence through the water jacket of the engine. Said fluid returns to the top part of the radiator through the usual connection.

The invention has for its objects to provide a pumping device of the character referred to which is adapted for ready attachment to engines of different kinds, and so having a considerable range of use, with attendant economy of manufacture and application; also to provide a convenient, readily attachable and strong support for such device when combined for use with an engine; also to accommodate the location and movements of the fan belt, so that the pumping element may be driven thereby without any tendency to displace the belt.

With such objects in view as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In said drawings—

Figure 1 is a perspective view of a portion of an automobile engine, having applied thereto a cooling pumping attachment, the same embodying the invention.

Fig. 2 is a longitudinal vertical section on line II—II of Fig. 3 of the pump attach-

ment removed from or before application to, the engine.

Fig. 3 is an end view with the screw cap removed and with the pump shaft shown in section.

Fig. 4 is a cross section on line IV—IV of Fig. 2.

Referring to the drawings, 1 indicates the engine, having a cooling water jacket, 2 the radiator, 3 the fan, 4 the fan shaft, 5 the fan belt, and 6 the circulation water elbow leading from the top part of the engine water jacket.

7 is a cylindrical pump casing forming the main body of the attachment and having within one end a shaft bearing 8 cast with said casing. At the other end, which may be termed the outer end, the casing 7 is closed by a cap 9 which is screwed into the end of the casing and is provided with a shaft bearing 10 and a stuffing box 11. 12 is a pump shaft mounted in said bearings 8 and 10 and terminating at its inner end within the casing and passing out at its outer end beyond the stuffing box, where it has fixed thereon a belt pulley 13 arranged to be in line with the fan belt 5 so as to be driven thereby, as indicated in Fig. 1. 14 is the pumping or water-circulating element, preferably in the form of a screw fixed on the shaft 12 near the bearing 8. 15 is a water-conducting branch from the casing 7 and cast therewith and extending down to within convenient distance of the radiator pipe 17, with which it is connected by means of 16 a rubber or other flexible pipe section 17 which is clamped in place in the usual manner of connecting such sections. When the engine and fan are in operation therefore, the pumping screw 14 draws the cooling fluid from the lower part of the radiator by the pipe 16 and branch 15 and propels it rearwardly towards the entrance of the water jacket, which is through the jacket elbow 18, the same being tightly secured to said jacket by bolts 19. The rear end of the casing 7 is formed beyond the bearing 8 with a short extension or branch 20, which, when the pumping attachment is put in place, will be within easy connecting distance of the jacket elbow 18, with which it is united by a flexible pipe section 21 and clamps 22. The casing is formed with an upwardly extending lug 23 to which is bolted a short casing-supporting bar 24 and the

105
110

- rear end of this bar has an eye through which is caused to pass one of said bolts 19, as seen in Fig. 1. At the exit of the water jacket is secured the said elbow 6 by bolts 25, and by one of said bolts is attached a depending casing-supporting bar 26 the lower end of which is secured by a bolt 27 to a lug 28 cast on and projecting from the rear side of the casing 7.
- 10 By the above construction and arrangement of parts the pumping attachment is self-contained, capable of manufacture, as a unitary device, in quantity and economically, and which can be applied to large numbers of engines now in use, so as to replace the lower connection between the radiator and water jacket, which connection has no water propelling means, or one which is not satisfactory.
- 15 20 The shaft 12 is mounted to be longitudinally movable, so as to accommodate itself to the location of the fan belt, and to its movements, so that there will be no tendency of the pulley 13 to displace the belt from its other pulleys. Said shaft 12 is freely movable endwise in its bearings, within limits, the pump screw abutment against the bearing 8 acting as a stop in one direction, and a collar 29 fixed on the shaft and adapted
- 25 30 to abut against the cap 9 serving as a stop in the other direction, these stops limiting respectively the rearward and forward movements of said shaft 12.
- What is claimed is—
- 35 1. In a cooler for engines, the combination of a horizontal tube constituting a casing and extending longitudinally of an engine at one side thereof, said tube being provided adjacent its front end with a depending branch outlet, a longitudinal shaft slidably mounted in the said tube and extending sub-
- stantially the entire length of the same concentrically thereof and provided at the rear end with a rotary pumping element located within the tube, means for limiting the longitudinal movement of the shaft, means for connecting the rear end of the tube with the water jacket of the engine and the outlet branch with the radiator, and a belt pulley fixed on said shaft and adapted to be engaged by the fan belt of the engine, the longitudinal movement of the shaft permitting the belt pulley to adjust itself automatically to the fan belt. 45 50
2. In a cooler for engines, the combination of a horizontal tube constituting a casing and extending longitudinally of an engine at one side thereof and provided adjacent its front end with a branch outlet, said tube having an interior bearing at its rear end and provided at its front end with a removable cap having a bearing, a shaft extending longitudinally of the said tube and slidably supported in the said bearings concentric with the said tube, the front end of the shaft 60 65 projecting outwardly beyond the cap, a rotary pumping element consisting of a screw mounted on the rear portion of the shaft within the said tube, adjustable means mounted on the shaft and operating with the pumping element to limit the slideable movement of the shaft, means for connecting the rear end of the tube with the water jacket of the engine and for connecting the branch outlet with the radiator of the engine, a belt 70 75 80 pulley mounted on the projecting front end of the shaft and arranged to receive the fan belt of the engine, the longitudinal movement of the shaft permitting the pulley to adjust itself automatically to the fan belt. 80

In testimony whereof I affix my signature.
HENRY NELSON SCHOFIELD.
